UNITED STATES PATENT OFFICE.

THOMAS S. LEWIS AND ALONZO L. LEWIS, OF MEMPHIS, TENNESSEE.

STRAW-HOLDER.

No. 926,581.

Specification of Letters Patent.

Patented June 29, 1909.

Application filed December 26, 1908. Serial No. 469,369.

To all whom it may concern:

Be it known that we, THOMAS S. LEWIS and ALONZO L. LEWIS, citizens of the United States, residing at 2164 Madison street, in the city of Memphis and State of Tennessee, have invented certain new and useful Improvements in Straw-Holders; and we do hereby declare the following to be a full, clear, and exact description of the invention, 10 such as will enable others skilled in the art to which it appertains to make and use the same.

Our invention relates to improvements in straw holders, and the object of our invention is to provide a simple device, of neat appearance, to hold the straws such as are usually used at soda fountains, protecting them from dust and flies and yet holding them in such a way that they may be readily reached 20 by the user without opening the holder. Our invention, however, is not confined to this use, as it is applicable to contain any long objects of small diameter, as pencils, for example.

25 With the objects stated in view, our invention consists in the construction and combinations of parts as hereinafter described and claimed.

In the accompanying drawings—Figure 1 30 is a perspective view of our invention, the cover being raised, and Fig. 2 is a central cross section of the same.

a represents one of the heads or end pieces, the upper part of which is practically circular 35 as shown at *b*, terminating in an outwardly curved portion *c*, provided with a downwardly beveled portion *d*. The whole device is supported on suitable legs *e*, one at each corner. Mounted on these heads is the body portion, 40 the main part of which is a partial cylinder as shown at *f*, terminating in an outward curve *g* in line with the curved portion *c* of the heads. The lower part of the body consists of two curved pieces *h* and *i*, meeting in a 45 point *j* and curved away from each other and extending downwardly to a line *k* under the edge formed by the curve *g*. The outer part of each of these pieces is then bent upwardly at an angle, as shown at *m*, leaving a longitudinal opening *n* through which the straws or 50 other articles may pass. The parts *h*, *i* and *m* are cut away in the center as shown at *o*, to permit the finger being placed underneath

one of the straws, or similar articles, to readily pull it out. This cut-away portion is 55 widest at the outside and gradually tapers inwardly, being at its inner end about the width of an ordinary finger. The top of the receptacle is open as shown at *p*, and this opening is adapted to be closed by a removable cover *q*, provided with end flanges *r* and pins *s* to keep the cover in place.

In using, the straws or other articles are dropped into the top and fall by gravity into the position shown on the left of Fig. 2, leaving one straw, and only one, ready to be pulled out. The peculiar shape of the parts *g*, *h*, *i* and *m* and the position of the slot *n* are of great importance in this connection, because they are so shaped that just one 70 straw appears in the opening *n*, the other straws lying against each other, as shown in Fig. 2, preventing the weight of the straws above from driving the exposed one out of the casing. The straws are simply dropped into 75 the receptacle and by a slight shake are compelled to lie longitudinally in the receptacle, which is slightly longer than the straws themselves.

The device may be made of any suitable 80 material, such, for example, as ordinary tin.

We claim:

A receptacle for straws and similar articles, consisting of a body portion having an opening in its top, a cover therefor, ends closing said body portion, and a double, inclined bottom, said body portion having its lower edges inclined downwardly and outwardly, and the parts of said bottom being joined together so as to separate the articles into two 90 parts, each part of the bottom being inclined downwardly and outwardly and terminating in an upwardly inclined portion, a narrow space being left between the edge of said upwardly inclined portion and the lower edge of 95 said body portion, said inclined portion of the bottom being centrally cut away, substantially as described.

In testimony whereof, we affix our signatures, in presence of two witnesses.

THOMAS S. LEWIS.
ALONZO L. LEWIS.
